VENT VALVE STRUCTURE

Peter Lawrence Mikeska, Chicago, Ill., assignor
to The Dole Valve Company, Chicago, Ill., a corporation of Illinois

Application July 1, 1946, Serial No. 680,710

2 Claims. (Cl. 137—122)

1

This invention relates to a vent valve and more particularly to an improved siphon structure therefor.

As is well known in the art, the usual radiator vent valve has a threaded nipple adapted to be screwed into a radiator or the like and through which nipple projects a downwardly depending curved swingable siphon tube for draining the water from the valve. Frequently in applying the valve to the radiator, the siphon tube gets injured or jammed and as a result, the siphoning is interfered with or if a tube is closed by crimping no water can flow through it. Modern "Slim tube" radiation has complicated the draining problem because of the small sectional area in the radiator tubes.

It is an object of this invention to provide an improved vent valve structure including a siphon tube which will more readily adjust itself to a proper position in radiator.

Another object of this invention is to provide a vent valve with a siphon tube structure which lends itself to economical manufacture on a large production scale.

Yet another object of this invention is to provide a vent valve siphon tube which will effectively drain water accumulating in the bottom of the valve from the valve into the radiator.

Another and still further object of the invention is to provide a resiliently flexible siphon tube for a radiator valve adapted to drain water from the valve in part by a capillary action.

In accordance with the general features of this invention there is provided in a vent valve structure, including the usual water collecting body, a threaded nipple for attachment to the radiator, and a siphon tube projecting through the nipple comprising a resilient spring wire swingable to a downwardly depending position in the radiator for draining the valve.

Other features of the invention relate to the provision of several different forms of means for holding the spring wire in a bent or angular condition, in one of which the means comprises an extension of the spring itself and in the other of which a separate strip is disposed inside and fastened to the ends of the spring to hold the spring in the bent angular shape.

Still other features of the invention relate to the manner in which the spring wire siphon valve is attached to the internal wall of the radiator nipple.

Other objects and features of this invention will more fully appear from the following detailed description taken in connection with the accom-

panying drawings which illustrate several embodiments thereof and in which:

Figure 1 is a side view of a vent valve provided with a resilient wire siphon tube embracing the features of this invention;

Figure 2 is an enlarged fragmentary cross-sectional view through a lower part of the valve and the nipple and showing the manner in which the siphon tube is carried thereby;

Figure 3 is an enlarged cross-sectional view taken on substantially the line III—III of Figure 2 through the spring wire siphon tube;

Figure 4 is a sectional view similar to Figure 2, but illustrating a modified form of means or strip for holding the siphon tube in angular or bent condition;

Figure 5 is an enlarged cross-sectional view taken on substantially the line V—V of Figure 4 looking in the direction indicated by the arrows and showing the fastening of the strip to the lower end of the spring;

Figure 6 is a fragmentary sectional view through a lower end of a modified form of spring and showing a different connection between the spring retaining strip and the lower end of the spring tube; and

Figure 7 is a sectional view similar to Figure 4, showing a still further modification of the invention wherein the spring siphon tube does not have any retaining strip or wire and is in a straight condition.

As shown on the drawings:

The reference character 10 designates generally a radiator vent valve which may be of any suitable or conventional construction, but includes an inner water accumulating chamber 9 at the bottom thereof, and wherein condensate is adapted to accumulate in a manner well known in this type of valve.

The valve is provided, adjacent its lower portion, with a threaded nipple 11, which is adapted to be screwed into a threaded opening in a radiator (not shown). It is so located that when the condensate or water 12 gets above a certain level, such water can flow through the nipple and out of the siphon tube 20 to be hereinafter described.

The threaded nipple 11 includes an internal curved flange 13 suitably anchored or fastened to the inside surface of the wall of the valve 10 (Figure 2). The nipple 11 has a longitudinal bore 14 terminating in an enlarged bore 15 extending into the interior of the valve 10. The internal end of this bore 15 is enlarged to provide a shoulder 16 for cooperation with the siphon tube structure 20, which I shall now describe.

In the first form of the invention, the siphon tube 20 is shown as being composed of a spring wire 19 having its upper end turned inwardly inside of the wire tube into an extension 21, which extends clear through to the lower end of the tube where it is turned outwardly at 22 so as to be interlocked with the lower end of the tube. In this manner, the resilient tube 19 can be held in a bent angular formation, as shown in Figure 2. In other words, the inwardly turned wire extremity 21 of the spring is of a length less than the overall length of the spring 19 so that when its end is fastened at 22 to the lower end of the spring, it will hold the spring in the angular form shown.

The upper end of the spring siphon tube 19 is suitably fastened inside of a metal ferrule 23. Any suitable means, such as soldering or the like, may be employed for anchoring the spring to the ferrule 23. The ferrule in turn is swivelly mounted in a washer 24, suitably anchored as by means of solder or the like, to the shoulder 16 of the nipple 11. It will be noted that the innermost end of the ferrule is flared outwardly at 25 so as to swivelly lock the ferrule to the washer 24.

In Figure 4 I have illustrated a slight modification of the invention wherein there is provided a tubular threaded nipple 30 having a longitudinal bore 31, which communicates with the angular bore 32, terminating in an annular shoulder 33. Projecting into the tubular nipple is a wire spring siphon tube 35 having an internal strip of metal 36 for holding it in angular form. This strip 36 is turned outwardly around the lower end of the spring at 37 to tightly grip the same. The other and upper end of the strip 36 is interlocked with the metal ferrule 38. The upper end of the spring tube 35 is suitably fastened in the bore of the ferrule as by means of solder, and the ferrule is in turn swivelly mounted in a washer 39, suitably fastened to the nipple shoulder 33.

It will be perceived, as in the first form, that the ferrule 38 has its inner end flared at 40 so as to swivelly lock the ferrule and tube 35 to the fixed washer. The upper end of the strip 36 holding the spring 35 is turned at 41 and interlocked with the flared edge 40 of the ferrule so as to hold the spring tube 35 in the angular shape shown.

In the slight modification shown in Figure 6 the spring tube 35' corresponds identically with the tube assembly 35, with the exception that the lower end 37' of the strip 36' is of a slightly different construction. This lower end is double backed upon itself at 45 and is channeled above the double backed portion so that the end of the spring wire 35' can be received between the spring 36' and strip end 37'.

In Figure 7 I have illustrated still another form of the invention wherein the threaded nipple 50 is provided with a bore 51 having an enlarged bore 52, through which bores extends a spring siphon tube 53 embodying the features of this invention. This spring tube assembly has its flared ferrule 54 swivelly mounted in a fixedly carried washer 55. In other words, this form of the invention is substantially identical to that shown in Figures 2 and 4, with the exception that the wire spring tube 53 does not have an internal strip or wire for holding it in angular shape. On the contrary the spring wire siphon tube extends straight out of the metal nipple 50.

In all forms of the invention the siphon tube is positioned inside of the radiator by the act of screwing the nipple into the radiator in the usual manner. In the first three forms of the invention the siphon tube will swing in the radiator by reason of its swivel mounting until its free end is lowermost. In the last form of the invention shown in Figure 7, the spring wire 53 upon contacting the inner surface of the radiator 10 can bend or flex downwardly for the purpose of conducting water from the vent valve 10 back into the radiator; or, the spring wire 53 can remain substantially straight, and as the radiator surface becomes wetted to form the other "water leg" of siphon, draining of the valve 10 is had but at a slow rate.

In all forms of the invention, except the case where the spring wire 53 in Figure 7 is straight or substantially straight even when installed in 20 a radiator, as is customary in the art, the water is siphoned from the vent valve 10 by the tube and is conducted in part by capillarity along the coils of the tube so that the water will be discharged from the free or lowermost end of the 25 spring wire tube.

In the first three forms of the invention, the tube is at all times held in a predetermined angular shape which may be substantially a right angle, whereas in the last form the tube can be designed so as to either remain substantially straight when installed in a radiator or else can be bent into an angular shape as the nipple is progressively screwed into the radiator opening.

Accordingly, I have provided a very simple but 35 effective structure for venting water from valves of the type used in steam or vapor radiators, and wherein the siphon tube may be very economically manufactured. Then, too, the resilient character of the spring siphon tube permits of 40 it to yield as it is installed so that it will not become dented, damaged or jammed in the act of mounting the valve on the radiator. In existing structures where a solid metal siphon tube is used, unless care is exercised, the tube is apt to 45 be damaged or jammed in the act of mounting the same, especially when modern "slim tube" radiation is used. This undesirable feature of previous structures has been eliminated in my new resiliently flexible siphon tube.

50 I claim as my invention:

1. As an article of manufacture, a vent valve structure having projecting therefrom a helical coil spring siphon tube for conducting liquid by capillarity along the coils of the tube.

55 2. As an article of manufacture, a vent valve structure having projecting therefrom a resilient wire siphon tube, said wire tube having an internal connecting element between its ends for holding it in a bent angular condition with its lower end depending from the valve in a position for insertion in a radiator opening.

PETER LAWRENCE MIKESKA.
